UNITED STATES PATENT OFFICE.

BYERS W. KADEL, OF BALTIMORE, MARYLAND, ASSIGNOR TO THE T. H. SYMINGTON COMPANY, OF NEW YORK, N. Y., A CORPORATION OF DELAWARE.

JOURNAL BOX.

Application filed June 29, 1922. Serial No. 571,705.

To all whom it may concern:

Be it known that I, BYERS W. KADEL, a citizen of the United States, residing at Baltimore, State of Maryland, have invented 5 certain new and useful Improvements in Journal Boxes; and I do hereby declare the following to be a full, clear, and exact description of the invention, such as will enable others skilled in the art to which it 10 appertains to make and use the same.

My invention relates to journal box wear plates and, generally stated, involves a renewable liner of durable construction adapted to be detachably connected to the 15 journal box of a railway car for preventing destructive wear upon the car truck pedestal jaws and the journal box associated therewith, the wear incident to the constant movement of the journal box with respect 20 to the pedestal being taken by the interposed wear plate or liner.

Particularly stated, my invention resides in the provision of a flanged wear plate or liner preferably of uniform thickness and 25 having an intermediate wearing surface spaced from the means detachably connecting the liner to the journal box, thereby permitting the maximum wear of the liner without reducing the strength value thereof 30 or otherwise affecting the means for securing said liner to the journal box.

Heretofore it has been customary to form attaching tongues at the ends of the liner immediately adjacent the wearing surface, 35 and as a result, the connecting tongues are relatively weakened by the wearing through of the liner at these attaching points. My present invention has been designed to overcome this difficulty and provide a liner 40 which can wear almost through before the attaching means becomes reduced in strength value.

Another object of the invention is to provide in combination with a journal box a 45 renewable liner formed with offset portions at each end of the wearing surface, and bendable tongues or tangs provided adjacent said off-set portions, said tongues being adapted to be pressed over and interlocked 50 with projections provided on the journal box.

The invention further consists in the provision of a journal box renewable pedestal way liner which can be inexpensively manu-

factured and easily attached to the side wall 55 of a journal box.

There are other features of the invention as will more clearly appear from the detailed description taken in connection with the accompanying drawings chosen to illustrate 60 the invention and in which—

Figure 1 is a view in side elevation of a railway car journal box showing my improved wear plates or liners applied thereto.

Figure 2 is a detail vertical sectional view 65 on the line 2—2 of Figure 1 of a portion of the journal box showing the liner attached thereto.

Figure 3 is a detail perspective view of a portion of a journal box showing my im- 70 proved liners applied thereto.

Figure 4 is a horizontal sectional view on the line 4—4 of Figure 1.

Figure 5 is a detail perspective view of a modified form of liner embodying my 75 invention.

In the drawings corresponding reference characters designate similar parts in the several views.

A railway car journal box is indicated by 80 the numeral 1, said journal box being provided with side wall portions and projecting adjacent ribs or flanges 2. In the type of journal box shown for purposes of illustrating my invention, the opposite faces of 85 the adjacent flanges 2 and the connecting side wall portion of the journal box are adapted to be lined with my improved wear plate 3. The innermost flanges or ribs and intermediate portion of the journal box are 90 cut away, as indicated at 4, to prevent contact with the equalizer bars, not shown.

The wear plate or liner 3 is preferably formed of relatively thin flat steel of uniform thickness throughout and is provided 95 with flanges 5 and 6, said flanges being adapted to engage the faces on opposite ribs 2 and completely line the pedestal ways. The intermediate wearing surface of the liner terminates short of the vertical opposite ends thereof, the portions immediately adjacent said wearing surface being offset to form relief bends at each end of the liner. Each offset portion 7 is located outside of a vertical plane passing through 100 the wearing surface, and as shown, is inclined away from said wearing surface, thereby providing a construction in which 105

the liner can wear to the maximum extent without affecting the attaching means now to be described.

Provided at the end of each offset portion 5 7 is a bendable extension forming a tongue or tang 8, said extension being located back of a vertical plane passing through the wearing surface and at a point remote therefrom. The upper tongue is adapted to be 10 clamped about a projection 9 formed on the journal box, the end of said tongue extending downwardly and substantially parallel with the wearing surface of the liner. The lower tongue is clamped around the bottom 15 edge portion of the side wall of the journal box, as shown.

The side edges of the tongue are preferably spaced from adjacent portions of the wear plate and more particularly the flanges 20 thereof, a slot 10 serving to space the upper tongue and adjacent offset portion from the flange 5, and slots 11 being arranged to space the lower tongue and adjacent offset portions from the respective flanges 5 and 6. Each bendable extension is adapted to 25 be bent out of the plane of the wearing surface of the liner to afford effective attaching means not affected by the wear incident to service conditions.

30 I do not wish to be understood as limiting my invention to the exact construction of tongues formed on the offset portions contiguous to the intermediate wearing surface, as other types of attaching means may be utilized, and located in offset and remote relation to said wearing surface.

In Figure 5 I have shown an embodiment 35 of my invention wherein the relief bends 12 of the liner are formed by offsetting opposite end portions immediately adjacent the flanges of the liner without slitting or otherwise spacing the offset portions and associated attaching tongues. The tongue or tang 13 in this construction forms a continuation of the relief bends, said tongue being adapted to be bent around a projection on the journal box, as hereinbefore described.

A flanged wear plate or liner constructed in accordance with my present invention, I have found in practice to increase the longevity of use thereof in effectively resisting the wear incident to axle thrusts, as well as wear incident to the relative vertical movement between the pedestal jaws and journal box. It will also be obvious that I have produced a relatively light and durable wear plate which can be inexpensively formed of pressed metal of uniform thickness.

60 I claim:

1. The combination with a journal box for pedestal trucks, and a wear plate or liner detachably connected thereto, said wear plate being provided with an inter-

mediate wearing surface, offset portions provided adjacent each end of said wearing surface, and means formed on said offset portions and spaced from said wearing surface for detachably connecting said wear plate to the journal box. 70

2. The combination with a journal box for pedestal trucks, and a wear plate or liner detachably connected thereto, said wear plate having an intermediate wearing surface terminating short of the vertical opposite ends of said plate, and means spaced from said wearing surface provided at each vertical opposite end of said plate for detachably connecting said wear plate 80 to the journal box. 75

3. The combination with a journal box for pedestal trucks and a wear plate or liner connected thereto, said wear plate being formed of a uniform thickness and having at each end thereof a relief bend, and means for connecting said plate to the journal box. 85

4. The combination with a journal box for pedestal trucks, and a wear plate connected thereto, said wear plate being formed with a wearing surface terminating short of the opposite vertical ends of said plate and having bendable portions forming offset continuations of said wearing surface 90 for connecting said wear plate to the journal box. 95

5. The combination with a journal box for pedestal trucks, and a liner, said liner being formed with a wearing surface and 100 having oppositely inclined end portions, said wearing surface terminating substantially at said inclined end portions, and means including bendable tangs or tongues provided on the ends of said inclined end 105 portions for connecting the liner to the journal box.

6. The combination with a journal box for pedestal trucks, of a liner, said liner having an intermediate wearing surface, 110 opposite end portions arranged adjacent the opposite ends of said wearing surface, said end portions being inclined away from said wearing surface, and means for connecting said liner to the journal box. 115

7. The combination with a journal box for pedestal trucks having a projection, and a wear plate connected to said journal box, said wear plate being formed of substantially uniform thickness throughout and 120 having at each end thereof a relief bend, and means adjacent said relief bends for connecting the wear plate to the journal box, said means being adapted to engage the projection on the journal box. 125

8. The combination with a journal box for pedestal trucks having a projection, and a wear plate connected to said journal box, said wear plate being of substantially uniform thickness throughout and having a re- 130

- lief bend adjacent the wearing surface of said plate, and means detachably connecting said plate to the projection on the journal box.
9. The combination with a journal box having flanges forming a pedestal way, and a flanged wear plate adapted to line said way, said flanged wear plate being formed of substantially uniform thickness throughout and having at each end thereof a relief bend.
10. The combination with a journal box having flanges forming a pedestal way, and a flanged wear plate adapted to line said way, said wear plate being formed with a relief bend at each end of the web portion of said plate, and means adjacent said relief bends for connecting the plate to the journal box.
11. The combination with a journal box for pedestal trucks, and a flanged liner having an attaching tongue, the side edges of said tongue being spaced from the adjacent portions of said liner.
12. The combination with a journal box for pedestal trucks, and a flanged liner having a wearing surface, tongues adjacent the ends of said wearing surface, the side edges of the tongues being spaced from adjacent portions of the plate, said tongues being adapted to be bent out of the plane of the wearing surface to afford attaching portions for connecting the liner to the journal box.
13. A wear plate for railway car journal boxes provided with a wearing surface, opposite end portions contiguous said wearing surface, said end portions being offset with relation to the wearing surface, and bendable means formed on the ends of said offset end portions.
14. A wear plate for railway car journal boxes provided with a wearing surface, end portions adjacent said wearing surface, said end portions being arranged in a different plane than said wearing surface and having means for attaching said wear plate to the journal box.
15. A wear plate for railway car journal boxes provided with a wearing surface, and end portions adjacent said wearing surface, said end portions extending substantially vertically of the wearing surface and being offset therefrom.
16. A wear plate or liner for railway car journal boxes, said wear plate having a relatively large intermediate wearing surface between the vertical ends of said plate, and means provided on the wear plate and spaced from said wearing surface, said means affording attaching devices for connecting the wear plate to the journal box.
17. A flanged wear plate of the class described having a web portion provided with an intermediate wearing surface terminating short of the ends thereof, and means spaced from said wearing surface and arranged intermediate the flanges of said plate for attaching the same to the journal box.
18. A flanged wear plate of the class described having a web portion formed with a relatively large intermediate wearing surface, and means positioned between the flanges of said plate and spaced vertically and laterally from said wearing surface for attaching the wearing plate to the journal box.
19. A flanged wear plate of the class described provided with a web having an intermediate wearing surface, offset portions adjacent said wearing surface and located between the flanges of the wear plate, and bendable members adjacent said offset portion adapted to afford attaching means for said wear plate.
20. A flanged wear plate of the class described provided with a web portion having an intermediate bearing surface, and relief bends offset with relation to said wearing surface, said relief bends being provided intermediate the adjacent flanges of said web portion.

In testimony whereof I affix my signature.

BYERS W. KADEL.
